UNITED STATES PATENT OFFICE.

JOHN C. GAITHER, OF WASHINGTON, DISTRICT OF COLUMBIA.

SLIDING RECEPTACLE OR DRAWER.

SPECIFICATION forming part of Letters Patent No. 742,854, dated November 3, 1903.

Application filed December 28, 1900. Serial No. 41,386. (No model.)

To all whom it may concern:

Be it known that I, JOHN C. GAITHER, a citizen of the United States, residing at Washington, District of Columbia, have invented **5** certain new and useful Improvements in Sliding Receptacles for Large Books and Drawers, of which the following is a specification.

My invention is an improvement in sliding receptacles or drawers, and while the invention **10** is particularly adapted as a support for heavy books, yet, as shown herein, it is also well adapted to ordinary sliding drawers.

The object of the invention is to provide **15** means which will lock the sliding receptacle or drawer when it has been drawn out of its casing or compartment its full length, so that it will be retained in that position against unintentional closing or complete withdrawal from its compartment, means being also provided to automatically release the locking **20** means.

To this end the invention includes coacting rigid stops on the receptacle and compartment or casing, together with a movable stop **25** normally arranged to engage the receptacle when arrested by the beforementioned stops to lock the receptacle against closure, and it further includes means controlled by the position of the receptacle for shifting said movable stop to release said lock.

The invention also includes the details of construction to be hereinafter described, and particularly pointed out in the claims.

In the accompanying drawings, Figure 1 is **35** a side elevation showing the sides of the compartment removed. Fig. 2 is a longitudinal section. Fig. 3 is a front elevation. Fig. 4 is an elevation of the inside of the front section of the sliding receptacle. Figs. 5 and 6 **40** are details. Fig. 7 shows a drawer arrangement. Fig. 8 is a back view of the sliding receptacle A.

In the accompanying drawings but a single compartment is shown holding a single receptacle A. Near the front edge of the compartment B, at the top and bottom thereof and near each side, rigid stops **45** a b are secured. Extending longitudinally centrally of the top is a rib c, which provides a guide for the receptacle. At each side of the bottom of the compartment is a raised portion or rib d, upon which the receptacle slides, and to these ribs

spring-stops e are secured. As will be noted, the shoulder g or part of each spring which forms the abutment is a little to the rear of the transverse plane of the rigid stops. From the bottom of the sliding receptacle rigid stops a' depend, which are placed in alinement with stops a and abut the same when the receptacle is drawn out its full length. At each side **55** of the receptacle, at the rear thereof, angular stops b' are pivoted in recesses h, the walls which define the same providing stops to prevent said stops b' tilting to the rear out of vertical position. When the stops are in vertical position, their free ends are in alinement with stops b and abut the same when the receptacle is drawn out its full length. It will be seen that the coaction of stops a a' and b b' arrests the receptacle before it can **60** be completely withdrawn from its compartment. The receptacle when in retracted position rests upon springs e, holding the same depressed, the ribs being recessed to accommodate the portions g thereof. In the **65** outward movement of the receptacle as soon as the rear edge thereof passes over the outer ends of springs e, which occurs simultaneously with the stops a a' and b b' coming into contact, said ends will spring up and the **70** portions g abut the rear face of said receptacle, so that it will be locked against inward movement. To permit the receptacle to be pushed in, the springs e must be depressed so that the receptacle may ride over the same, **75** and this object is obtained by the provision of two plungers i i, guided on the rear face of the receptacle in vertical alinement with said springs.

Lateral extensions m m from the upper ends **80** of the plungers are guided in recesses in the rear wall of the receptacle and are pressed normally upwardly by springs n, held in sockets therein. These springs normally hold the ends of plungers i i above the free ends of **85** springs e and the forward ends of the latter extensions m m, which are flattened, in contact with the under side of the compartment. To depress the springs e e, the forward end of the receptacle is tilted upwardly, which **90** will force down extensions m m and there-through plungers i i, the latter forcing down the springs e. The sliding receptacle is slid rearwardly while the parts are in this position **95**

until the rear edge thereof passes over the free ends of said springs.

The operation of the invention will be understood from Fig. 1, which shows the receptacle drawn out and held by the vertical face *g* of the spring *e* against retracting movement. It will be seen that if the forward end of the receptacle is raised it will turn on its rear or inner edge as a pivot and throw the projection *m* against the upper wall of the compartment, thus causing the plunger *i* to be depressed and force spring *e* downwardly, so as to withdraw its face *g* from the rear end of the receptacle. The receptacle can now be moved inwardly.

To remove the receptacle entirely from the casing, the pivoted stops are thrown down. To permit this, the side edges of the top of the compartment are recessed, as shown at *n*, Fig. 1.

The modification shows an ordinary sliding-drawer arrangement similar in all respects to the construction just described except that the pivoted stops are eliminated and the upper ends of the plungers *i* are provided with extensions which coact with the rigid stops depending from the top of the compartment.

The device illustrated in Figs. 1 to 6 is intended to be used as a support for large books. For this purpose the base of the sliding receptacle is concaved to receive the back of the book, while the sides are held together at the inner edge by yoke *l*, the tines of which are independently pivoted to arm *u* and held in adjusted position by a thumb-nut *u*', the arm being pivoted in a bracket secured to the back of the sliding support. The yoke *l* in holding the book closed fits over the sides, the distance between the tines being adjusted to accommodate books of different thicknesses, the arm *u* being thrown up when it is desired to open the book. The front of the support is made in two sections *C C'*, hinged together at their lower ends and secured to the base, the upper ends of the sections being detachably secured together by means of the spring-pressed latch *V*, pivoted to one section *C*, engaging a stud on the opposite member *C'*, as shown in Fig. 5. The sections *C C'* carry supports *D* and *D'* for the book, which are yieldable, so as to accommodate books of different thicknesses. Stops are provided on the ends of the base to limit the outward swing of the sections. A dowel-pin may be carried by one section to fit within an opening in the other to hold the two tightly together. The swinging sections *C C'* are each provided with studs *F*, adapted to engage slots in the base of the sliding receptacle, so as to hold said sections in an upright position when the book is closed.

I claim as my invention—

1. The combination with a compartment and a receptacle adapted to slide therein, of means for arresting the movement of the receptacle against further outward movement when it has been withdrawn its full length and means to lock the receptacle against inward movement, substantially as described.

2. The combination with a compartment and a receptacle adapted to slide therein, of means for arresting the movement of the receptacle against further outward movement when it has been withdrawn its full length, means to lock the receptacle against inward movement, and means for releasing said locking means, substantially as described.

3. The combination with a compartment and receptacle adapted to slide therein, of means for arresting the outward movement of the receptacle, means for locking the receptacle against inward movement comprising a spring adapted to abut the rear of said receptacle and means for depressing said spring to permit of the inward movement of the receptacle comprising a vertically-movable plunger, substantially as described.

4. The combination with a compartment, a receptacle adapted to slide therein, a spring secured to the base of the compartment having a portion designed to engage said receptacle to prevent the inward movement of the same, a plunger carried by said receptacle adapted to align with said spring and a lateral extension of the plunger adapted when said receptacle is tilted to force the plunger down to move the spring out of locking engagement with the receptacle, substantially as described.

5. In combination in a book-support, a compartment and a sliding support comprising a base and a sectional front bar, said sections being pivoted together at their lower end and a detachable connection between the upper ends of said sections, substantially as described.

6. In combination in a book-support, a compartment and a sliding support comprising a concave base, a sectional front bar, a yielding book-support carried by said sections, a yoke having adjustable arms for engaging the book and an arm carrying said yoke pivoted to the rear bar of the support, substantially as described.

In testimony whereof I affix my signature in presence of two witnesses.

JOHN C. GAITHER.
